APPARATUS FOR MOUNTING A ROLLER IN A CAVITY IN A MEMBER

Marcel Royer, St. Eustache sur le Lac, Quebec,
Canada

Application May 28, 1947, Serial No. 751,160

2 Claims. (Cl. 1-1)

1

The present invention pertains to the mounting of a roller in the cavity of a member such as the header strip of a Venetian blind. According to present methods this is an awkward and inexact operation, due to the difficulty of properly supporting the roller while the axle pin is being driven into the rail. The object of the present invention is to provide a novel apparatus and method for performing this operation.

According to the invention there is provided a rest block having a seat in which the roller can be supported. The rail or other member is next inverted and adjusted so that its cavity receives the rest block and roller. The roller is thereby properly positioned in the cavity and is ready for the driving of the axle pin.

For the latter purpose there is provided a guide which is preferably in the form of a block with a groove adapted to hold the pin in axial alignment with the roller. A mechanical hammer is then preferably employed to drive the pin into the header rail and axially through the roller.

The invention is fully disclosed by way of example in the following description and in the accompanying drawings in which:

Figure 1 is a perspective view showing the invention in use;

Figure 2 is a longitudinal section of the apparatus;

Figure 3 is a similar section showing a roller mounted therein;

Figure 4 is a similar section showing the header rail mounted over the roller;

Figure 5 is a section similar to Figure 4, showing the pin driven through the roller;

Figure 6 is a section on the line 6-6 of Figure 5;

Figure 7 is a detail corresponding to Figure 5, and showing the rail and roller removed from the apparatus; and

Figure 8 is a plan view of Figure 4.

Reference to these views will now be made by use of like characters which are employed to designate corresponding parts throughout.

In several of the figures is shown a rail 1 having a cavity 2 in which a roller 3 is to be mounted. The rail 1 may be, for example, the header rail of a Venetian blind. As shown in Figures 5 and 7, the roller is not flush with the open end of the cavity nor does it engage the bottom of the cavity, inasmuch as it must turn freely. Consequently, the operation of mounting the roller in the cavity is ordinarily a difficult and awkward process, and the nail which is driven through the roller as an axle is not uniformly and accurately located.

2

According to the invention there is provided a rest block 4 having in its upper surface a concave seat 5 adapted to support the roller 3, as shown in Figures 3 and 4. The block 4 has the width of the cavity 2, and the rail 1 is laid, with the cavity 2 downward, in such manner that the cavity receives the block 4 and the roller supported thereby, as shown in Figure 4. The block 4 may be located on a base 6 by pins 7 if desired.

Adjacent to the rail 1 is mounted a guide block 8 having a groove 9 adapted to receive a pin 10. It will be understood that the block 8 may readily be mounted on the base 6 in a manner to position the bottom of the groove 9 and hence the nail 10 in alignment with the axis or center of the seat 5. A flat spring 11 having a nail hole 11' is bound around the block 8, with its free ends 12 forming a narrow space co-axial with the groove 9 and disposed between the block 8 and the rail 1. The space is adapted to receive the point 13 of the pin and thus serves as a guide for the pin as it is driven into the rail 1 by means that will presently be described.

Adjacent to the tapered end 14 of the pin 10 is mounted a mechanical hammer 15 with its plunger 16 adapted to engage the head 14. As the pin 10 is advanced by the hammer, the tapered head 14 eventually is forced through the space between the ends 12 and is finally embedded in the rail 1, as shown in Figure 5. The rail is then withdrawn from the block 4, and the roller 3 is mounted therein by the pin 9 and in the desired position, as illustrated in Figure 7.

Although a specific embodiment of the invention has been illustrated and described, it will be understood that various alterations in the details of construction may be made without departing from the scope of the invention as indicated by the appended claims.

40. What I claim as my invention is:

1. An apparatus for mounting a roller in a cavity of a member, comprising a rest block adapted to fit in such cavity and having a seat adapted to support a roller, a guide block having a groove aligned coaxially with said seat and adapted to support a pin, and a flat spring bound around said guide block and having its ends spaced apart at the end of said groove nearer said rest block.

50. 2. An apparatus for mounting a roller in a cavity of a member, comprising a rest block adapted to fit in such cavity and having a seat adapted to support a roller, a guide block having a groove aligned coaxially with said seat and adapted to support a pin, and a flat spring bound

55

around said guide block and having its ends spaced apart at the end of said groove nearer said rest block, and means for driving the pin from said groove to said space and toward said seat.

MARCEL ROYER.
